(57) **CLAIM**

The ornamental design for a L.E.D. light sensor head, as shown and described.

DESCRIPTION

FIG. 1 is a top perspective view of the L.E.D. light sensor head.

FIG. 2 is a bottom perspective view of the invention.

FIG. 3 is a top plan view of the invention.

FIG. 4 is a bottom plan view of the invention.

FIG. 5 is a front elevation view of the invention.

FIG. 6 is a rear elevation view of the invention.

FIG. 7 is a right elevation view of the invention; and,

FIG. 8 is a left elevation view of the invention.
